AUTOMATIC ACETYLENE GAS GENERATOR

Rolland C. Sabins, White Bear Lake, Minn.

Application September 12, 1935, Serial No. 40,258

13 Claims. (Cl. 48—19)

My invention relates to an automatic acetylene gas generator, wherein a portable gas generating unit is provided. The unitary construction of my generator provides a compact device which may be easily carried and set up wherever it is desired for use.

A feature of my automatic acetylene gas generator resides in an inclosed unit wherein an air sealed cell is provided which forms an inclosed air cushion within the generator. This air cushion is sealed within the generating unit and in the building up of gas pressure within the unit the air cell is compressed so that the water may recede from the carbide when the pressure reaches a predetermined point within the unit. The air cell is of a simple construction and may be formed of rubber and adapted to fit into one end of the tank, forming the unit of the generator and containing a predetermined volume of air which is hermetically sealed within the cell.

It is also a feature to provide my generator with an adjustable carbide cake supporting means which may be adjusted in position within the tank of the generator so that a predetermined pressure of gas may be maintained within the generator in accordance with the setting of the carbide cake supporting means. The adjusting means for the carbide cake supporting means may be positioned on the outside of the generator where it is accessible for adjustment.

My generator is formed so that it may be taken apart and cleaned and replenished with the carbide cake from time to time. The generator also includes a safety valve means, a pressure gauge means, a screen and filter means.

In a form of my generator, the air cell or chamber which provides the cushion for the gas in the generator, may be built in the tank of the generator and in this construction a suitable flexible diaphragm is provided. This construction also includes a means of supplying air pressure to the air chamber below the diaphragm.

In a form of my generator one portion of the tank thereof is provided with an air cushioning chamber which extends about the gas chamber. This is formed by a double cylindrical wall construction, the inner cylinder extending down into the bottom and being sealed at the top. In this construction, the air cushion is formed about the gas chamber so that when the gas pressure builds up, the water may be forced down away from the carbide cake and up in a manner to compress the air in the air chamber.

Further, my generator is provided with cam lever means for locking the upper and lower units,

together in a simple and effective manner so that when the generator is closed it is hermetically sealed from the outer atmosphere. I also provide a suitable carrier for the lower portion of my generator which permits the lower portion which contains the adjustable carbide cake supporting means to be carried by a suitable bale. This permits the lime and water residue to be easily cleaned out and replenished with fresh water and new carbide cakes.

Further, my generator is provided with a flexible sealing joint of a peculiar nature which permits the rotation of the adjusting shaft for the carbide cake supporting means from outside of the tank and provides a perfectly water and gas tight joint without using a packing gland joint. This form of seal for the adjusting shaft is very desirable because it does not retard the movement of the adjusting shaft. Further, this sealing joint is particularly adapted where a limited movement is desired between the parts and where a flexible seal is required. This sealing joint may be economically made and has an indefinite lasting quality and requires no attention.

The structure of my gas generator provides a means of suspending the water within the generator between the carbide cake and the air cushion. The air cushion is hermetically sealed in this construction from the water and by suspending the water between the air cushion and the lower end of the carbide receiving receptacle and sealing the air from direct contact with the water or the generated acetylene gas, a more practical generator device is provided and the air cannot mix with the acetylene gas and water, and thus I provide a safer acetylene gas generator. Further, by sealing the air in the lower portion of the gas generator in a separate compartment, should the walls of the air compartment break down, the water level in the generator would simply lower to such an extent as to make the generator just that much more safe against the generation of the gas owing to the fact that such a condition would change the normal water level.

These features, together with other details and objects will be more fully and clearly set forth in the specification and claims.

The drawings show a means and apparatus of carrying out my method.

Figure 1 illustrates inside elevation my automatic acetylene gas generator apparatus.

Figure 2 is a vertical cross section of my gas generating unit in one form of the same where an air cell is used within the generator tank.

Figure 3 illustrates a vertical section of another form of my portable gas generator apparatus.

Figure 4 illustrates still another form of my portable gas generator apparatus.

Figure 5 is a section on the line 5—5 of Figure 2, in the direction of the arrows.

Figure 6 is a section on the line 6—6 of Figure 3, in the direction of the arrows.

Figure 7 is a vertical section on the line 7—7 of Figure 4, in the direction of the arrows.

Figure 8 is a section on the line 8—8 of Figure 3, in the direction of the arrows.

Figure 9 is a vertical sectional detail of the sealing joint for the carbide cage operating mechanism used in Figures 1, 2 and 5.

My unitary gas generator apparatus A is formed with an upper tank portion 10 and a lower or base tank portion 11. The tank portions 10 and 11 are held together by the cam operating clamps 12. It is desirable to provide the portable generating tank A with three or more clamps 12 equally spaced apart and carried by the lower portion 11 of the tank. The cam clamps 12 consist of a hook 13 which is adapted to fit over the sealing flange 14 which is integrally connected with the upper tank portion 10. A suitable annular sealing gasket 15 is positioned within the flange 14 against which the upper edge 16 of the lower portion 11 is adapted to bear to seal the tank portions 10 and 11 tightly together. The hooks 13 of the cam clamps 12 are formed on the upper end of the rod 17. The rod 17 is rotatably supported in the boss portion 18 which is secured to the tank portion 11. The lower end of the boss 18 is formed with a cam surface 19. Upon the lower ends of the rods 17 are rotatably secured cam portions 20 which cooperate with the cam surfaces 19 to draw the hooks 13 down tight against the flange 14. The cam portion 20 is operated by suitable handles 21 which have an arcuate shape so that they may lie against the cylindrical outer surface of the portion 11 of the generator when the hooks 13 are in locked position. The hooks 13 are placed in locking position and then the cam 20 is operated by the handle 21 to draw the hooks tight. The cam 20 is held upon the rod 17 by the nuts 22.

In the structure of the generator A illustrated in Figures 1 and 2, the lower tank portion 11 is adapted to support a rubber or flexible air cell B which contains a predetermined volume of air and which is flexible so that it may be compressed. The lower tank portion 11 contains the water over and about the cell B.

The carbide cage supporting cage 23 is slidably supported by the side members 24 so that its relative position within the generator A can be adjusted. I provide a suitable carrying bale 25 which normally lies down when the generator is put together, as illustrated in Figure 2, but which can be raised up as illustrated in Figure 3, so that when the generator A is taken apart by loosening the clamps 12, the lower portion 11 can be carried by the bale 25. The guide portions 24 have a T cross-sectional shape, whereas, the cage 23 for the carbide cage is formed with 70 guide channels 26 which extend the length of the cage 23. The cage 23 has open slots 27 formed in the bottom of the same so that the water may be brought into contact with the lowermost cake of carbide resting in the cage 23 when the gas pressure in the generator A recedes

below a normal or predetermined pressure for which the generator A is set.

The cage 23 is adapted to be operated by the shaft 28, the formation of which is more clearly illustrated in Figure 8. This shaft 28 is formed with a bell crank end 29 which engages the link 30. The link 30 is connected at 31 to the side of the carbide cage 23. The shaft 28 is supported on its inner end by a bearing 32, while the outer end extends through a bearing sleeve 33, which 10 sleeve is welded integral to the side wall of the tank portion 11. A sleeve 34 is welded or integrally connected to the shaft 28 adjacent the bearing 32 and form a sealing joint between the sleeve 33 and the integral sleeve 34 by interposing between the same and extending over the shaft a rubber hose 35 formed of a pure gum rubber so as to make the same tough and long wearing. The hose 35 is held by hose clamps 36 to the sleeves 33 and 34, respectively. 20

The shaft 28 is operated by the lever 37 which is positioned on the outside of the shank portion 11 as illustrated in Figure 1, and which connects with the square end of the shaft 28. The lever 37 is operated on the gauge quadrant 38 25 and is held in adjusted position by the wing nut 39. The gauge marks 40 indicate the pressure of the gas for which the tank is set so that it will automatically generate the gas pressure indicated by the gauge marks 40 when the lever 37 is set at 30 a predetermined point by the wing nut 39. The adjustment of the shaft 28 regulates the position of the carbide cage 23 within the generator A, as it will be apparent that the cage 23 can be raised and lowered by rotating the shaft 28. The 35 guides 24 holds the cage 23 in slidably position.

It will also be apparent that the sealing joint which is made up of the flexible rubber hose 35 and the hose clamps 36 provide a seal which is absolutely tight and will not leak gas or water 40 in the operation of the shaft 28. This provides a novel sealing means so that the shaft 28 may be operated from outside of the tank portion 11 and is of a simple nature, requiring practically no attention until the flexible rubber hose has 45 entirely worn out.

It is desirable that the adjusting means for the gas pressure be outside of the generator A so that it may be set at no pound pressure while opening or closing the generator, and to the desired number of pounds that the generator A is adapted to operate for when it is closed, so as to maintain a gas pressure within the same according to the setting of the lever 37 on the quadrant 38. 50

The upper portion 10 of the generator A is provided with a screen 41 which is held in place by the nuts 42 on the lower end of the pipe 43. The screen 41 extends down in a conical shape and is adapted to support the filter 44 which may be 60 of any suitable material. 55

The pipe 43 extends on through the top of the generator and supports the safety valve 45 which is positioned on top of the generator A to provide an escapement of any excess gas pressure. The 65 generator A is provided with a gas supply or outlet pipe 46 in which the shut-off valve 47 is interposed and also a pressure gauge 48 to indicate the gas pressure in the generator.

I provide a carrying handle 49 on top of the 70 generator A and a side carrying handle 50 which facilitates the handling of the same and so that it can be carried from place to place if it is desired. My method of generating gas is carried out by a unitary self-contained gas generating 75

apparatus which is hermetically sealed and which is adapted to automatically keep a predetermined gas pressure within the same.

In operation the lever 37 is set into the desired position when the generator is closed, to indicate the pounds of pressure desired in the tank. The cell B is in place in the lower part of the generator A and a sufficient amount of water is placed within the same so that when the lever 37 is adjusted to the desired position the calcium carbide cake which has been placed in the cage 23, will come in contact with the water, whereupon acetylene gas will be generated, filling the upper portion of the tank 10. As soon as the gas pressure has reached the predetermined setting of the lever 37, it will force the water down against the air cell B, compressing the same sufficiently to lower the water automatically away from the carbide, stopping the generation of the gas without in the generator A. As the acetylene gas is drawn out of the generator A through the outlet 46 and the pressure of the gas drops below the pressure indicated by the setting of the lever 37, the water in the generator A will be caused to rise by the expansion of the cell B, so that the water will contact the carbide in the receptacle 23 to start the generation of gas. Then as soon as the pressure of the gas reaches the predetermined setting of the lever 37, the water will be again forced away from the carbide, compressing the cell B, and automatically shutting off the generation of gas in the generator. In this manner the generator operates automatically to start and stop the generation of gas. The safety valve 45 protects the generator against excessive gas pressure within the same. The generator is simple in operation and may be readily set up in any place where it is desired for use.

In the construction illustrated in Figures 1 and 2, the carbide cage 23 is held between the guides 24 and the lower ends of the guides 24 fit in the channels 51 which extend along the inside of the lower portion 11 of the generator A to support the lower ends of the guides 24. This construction permits the guides to be removed when it is desired to replace the cell B.

The upper ends of the guides 24 are held spaced apart by the ring 52, and the bale 25 engages as heretofore set forth, to permit the lower end 11 to be carried when the generator A is taken apart. Thus I provide a suitable carrying means for the lower portion 11 of the generator A, so that when it is taken apart it may be lifted by the bale 25 and carried to a suitable place where the water and carbide cake may be renewed. This construction is carried out in the forms of my generator shown in Figures 1 and 2, and also in Figure 3, and as shown in Figures 4 and 5.

The seal for the operating rod 28 which was described heretofore as shown in Figures 3 and 8, is for the type of generator A' shown in Figure 3. In this construction, the operating rod 28 is secured at the bottom of the portion 11.

In the construction of the generator in Figures 1, 2, 5 and 9, the seal is of the identical construction, using the flexible tube 35 which is held by the hose clamps 36 on the end, however, in the construction of this generator A, the operating rod 28 is formed with its crank end 29 bent back at 29', as shown in Figure 9, so as to connect with the link 30 which operates the cage 23 to raise and lower the same. In this construction there is no inner support 32 for the rod 28, the rod 28 being supported by the long bearing nipple 33 which is welded to and extends through

the side of the tank portion 11 positioned up from the bottom at a point above the air cell B. Thus the operating rod 28 in the structure of the generator A of Figures 1, 2, 5 and 9, operates above the air cell B instead of down on the bottom as shown in Figure 8 and as used in the construction of Figure 3 of my generator. Where the air cell B is used, it is desirable to remove a portion of the operating mechanism which raises and lowers the carbide supporting cage 23 in placing the cell B in the lower part of the generator portion 11 or in removing the same, and by disengaging the lever arm 37 from the outer squared end of the rod 28 and removing the inner hose clamp 36 and then disengaging the end 29' from the link 30, this operating mechanism may be removed leaving a passageway for the insertion or removal of the air cell B.

In the form of my generator A' shown in Figure 3, the carbide cage 23' is provided with the openings 27' in the bottom of the same and the cage slides up and down between the guides and supports 24'. The lever 27 adjusts the rod 28 to move the crank arms 29 and thus operate the link 30 to raise or lower the position of the carbide cage 23' in this form of my generator A'. In this construction, the guides 24 run straight down to the bottom and are welded or otherwise secured integrally with the bottom of the generator.

The generator A' is also formed with an upper portion 10' and a lower portion 11' which are adapted to be separated as heretofore set forth, in the construction of the generator A in Figures 1 and 2, the cam clamp 12 holding the portions together.

In the form of the generator A', I do not use the inclosed air seal in the bottom of the same, but in this construction the air cushion is provided by a separate internally positioned and integrally secured cylindrical sleeve 53 which is secured at 54 in the top of the portion 10'. This sleeve 53 is spaced from the outer wall of the upper portion 10' and projects down into the bottom portion 11' of the generator, as illustrated in Figure 3. The sleeve 53 forms an air chamber 54 about the gas compartment 55 in the generator A', so that when the gas pressure builds up in the chamber 55 in the operation of the generator, the water in the bottom 11' is forced up in the chamber 54, compressing the air in the chamber 54 sufficiently to permit the water to recede away from the openings 27' and the carbide in the cage 23'. In this manner the generator A' operates automatically the same as the generator A to supply a predetermined pressure of gas in the chamber 55 which may be drawn through the pipe 46 as it is needed. Thus gas is generated automatically by the raising and lowering of the water to contact the carbide in the cage 23'.

I have shown another form of my gas generator in Figure 4, and this generator A'' is adapted to automatically generate acetylene gas or other similar gas as it is required in the generator A''. All of these generators illustrated are for the purpose of showing the manner in which I carry out my method of automatically generating acetylene gas or other gases where it is desired to provide a supply of the same at a predetermined pressure and have the same general construction in the top thereof which provides the filter 44 and the screen 41 which may be removed by removing the collar nut 42. All of the generators are supplied with a safety valve 75

45 and a pressure gauge 48, as well as a shut-off valve 47.

In this type of the generator A'', the carbide cage 23'' is supported by the clamping means 53 in a set position within the upper portion 10'' of the generator. The clamp 56 may be made in any suitable form and is illustrated in one of these forms in Figure 7. Here the clamp 56 is illustrated with a ring nut 57 which may tighten 10 or loosen the clamp about the carbide cage 23'' so that the cage may be adjusted into the desired position or may be removed when it is desired to replenish the carbide cake so that a new supply of calcium carbide may be placed within 15 the cage 23'' after the old lime residue has been removed.

The generator A'' is constructed with an air sealed chamber B' in the base portion 11''. The chamber B' is made by providing a flexible sealing disc 58 across the bottom of the generator 20 which is sealed in place so as to provide an air tight compartment B' in the lower portion 11'' of the generator A''. The generator A'' is provided with an air pump C which connects 25 through the check and release valve 59 to the air chamber B'. The air pump C is adapted to regulate the air pressure within the air chamber B' and in this manner the water level within the generator A'' may be varied according to 30 the air pressure within the chamber B'. In this form of the generator as the gas is built up in the upper portion 10'' the water level will be forced down away from the carbide cage 23'' so as to automatically stop the generation of gas 35 when the pressure of the gas has reached a predetermined point.

In the generator A'' the adjustment of the pressure of the gas is regulated by the air pressure in the chamber B' and the air is supplied 40 by the pump C. In this form of my generator it is not necessary to provide an adjusting means with an outer lever, such as 37, for regulating the position of the calcium carbide cage 23''. The acetylene generating operation, however, is 45 the same in this generator as in the others, in that the gas is automatically generated up to a predetermined point, whereupon the generation of gas ceases until the pressure of the gas recedes. When the gas pressure recedes, the water 50 level is raised up to the calcium carbide by the air in the chamber B', thus starting the generation of gas.

The apparatus discloses forms of generators which may be used in carrying out my method 55 of automatically generating acetylene gas in a simple manner, with sealed containers of a unitary character which are portable and which are safe to operate. My method which includes the sealed air cushion generator is very desirable 60 because it separates the air cushion entirely from the water and acetylene gas, making the generator more safe and readily responsive to operate to automatically maintain the desired gas pressure within the generator. My method consists in automatically generating the acetylene 65 gas in a unitary sealed generator, wherein an air cell or sealed air chamber is provided with a predetermined volume of air, or where the volume of air may be increased or decreased as 70 may be desired, the check valve 59 being formed in a manner so that it may be released to permit some of the air to escape from the chamber B'.

Thus my method is carried out by suspending a quantity of calcium carbide in an adjustable 75 container above a volume of water and provid-

ing a sealed air cushion, and causing the water to automatically raise and lower into and out of contact with the calcium carbide or similar substance to automatically maintain a predetermined gas pressure within a container. The generators disclosed carry out this method and are of a simple structure which may be readily operated when set up and charged for use. Further, the generators being of a unitary character are completely sealed yet they may be opened and cleaned from time to time and provided with a new supply of calcium carbide and water in an easy manner so as to simplify the maintenance of these generators.

In accordance with the patent statutes I have described the principles of my method and generator apparatus which I have disclosed to assist in carrying out my method and it is apparent that variations may be made in the construction of said apparatus without departing from the spirit of my invention when interpreted within the scope of the following claims.

I claim:

1. An acetylene generator including a container having walls, and a liquid and gas tight flexible joint comprising a stationary nipple secured to a container wall, a movable member extending through said nipple to the inside of the container, a flexible hose-like sealing member, clamping means to secure said sealing member to said nipple on one end, and clamping means for securing said flexible member to the movable member extending through said nipple into the container to provide a sealing joint for said movable member providing a liquid and gas tight connection between the wall of the container and the movable member.

2. An acetylene gas generator including a gas compartment, an adjustable support for a calcium carbide cake adapted to form a gas upon 40 contacting water, a water compartment, resilient compressible means beneath the water level of said water compartment compressible by an increase in gas pressure within the gas compartment to move said water level out of contact with said cake, means outside of said generator for setting said cake support for automatically maintaining a predetermined gas pressure in said generator.

3. An automatic acetylene gas generator comprising a calcium carbide cake support, a water compartment, and a hermetically sealed expandable and contractable air compartment in said water compartment beneath the water level, a flexible resilient partition permanently separating 55 said water and air compartments, said air compartment contracting upon an increase of gas pressure to decrease its volume and thus to lower the water level.

4. An acetylene gas generator comprising a 60 container, an adjustable supporting means within said container for calcium carbide, means extending from the outside of said container connected to said supporting means to adjust the same, a water compartment in said container, an air cushion compartment in said container adjoining said water compartment, and a flexible sealing joint for said adjusting means for said carbide supporting means, said sealing means including a flexible tubular member bound 65 on each end by sealing clamps to hold one end thereof stationary with the container casing and the other end movable with the adjusting means for the carbide container.

5. An acetylene gas generator including a tank 75

adapted to contain water in the base thereof, a resilient expandible and contractable sealed flexible compartment in said tank below the water, said compartment varying in volume in inverse proportion to the gas pressure in said tank to raise or lower the water level, a calcium carbide cake support, and means for adjusting said carbide cake supporting means to set the same in a manner to maintain a constant gas pressure automatically in said tank by raising or lowering the water level in accordance with the pressure of the gas within said tank.

6. An acetylene gas generator including upper and lower sections, means for sealing said sections together, a hermetically sealed air compartment positioned in the base of said generator, said air compartment being capable of compressing under pressure to considerably lower the water level, a water compartment contacting said air compartment and providing a water level above said air compartment in said generator, a resilient flexible partition permanently separating said air and water compartments, a calcium carbide container, and means for setting said carbide container in a predetermined position in said generator in relation to the water level, whereby a predetermined acetylene gas pressure will be maintained in said generator.

7. A portable acetylene gas generator including a sectional gas tank having upper and lower portions, means for sealing said portions together, an adjustable holder for calcium carbide cake supported in said lower portion, a valved gas outlet, a sealed compressible air cushion compartment below the water level in said generator compressing upon an increase of gas pressure in said tank to lower the water level beneath said holder, and a resilient flexible partition permanently separating said air cushion compartment from said water compartment.

8. An acetylene gas generator including a unitary, portable tank, an adjustable calcium carbide cake holder in said tank, a filter outlet, a flexible diaphragm extending completely across said tank forming a compressible air compartment hermetically sealed in said tank, a water compartment above said diaphragm and air compartment, whereby a predetermined gas pressure in said tank will depress said diaphragm and compress said air compartment to automatically lower the water level within the tank beneath said holder and stop the generation of gas within.

9. An acetylene gas generator comprising upper and lower portions, means for sealing said portions together, a gas chamber in said upper portion, a valve release gas outlet leading from said upper portion, a calcium carbide supporting means adjustably suspended within said tank, a compressible air chamber within said tank, a water compartment above said air chamber associated with said compressible chamber, a resilient flexible partition permanently separating said air chamber from said water compartment, said compressible chamber being compressed by an increase in gas pressure to lower the water level beneath said calcium carbide, and means outside of said generator for setting said carbide support in a position in relation to the water level in said generator to automatically cause the generation of acetylene gas within said generator to build up a predetermined gas pressure and

automatically maintain the same by raising and lowering the water level within said generator.

10. An automatic acetylene gas generator including a gas chamber, a water chamber, a safety valve, an adjustable receptacle adapted to support in suspension calcium carbide, a compressible hermetically sealed air chamber below the water level, and a flexible resilient partition between said air chamber and said water chamber, whereby the water level within said generator may be automatically raised and lowered by decreases and increases respectively, of gas pressure built up within the generator to maintain a uniform gas pressure within the generator to provide a uniform supply of gas therefrom.

11. A separable acetylene gas generator including upper and lower portions, means for sealing said portions together, a gas chamber in said upper portion, means for slidably suspending calcium carbide within said chamber, a hermetically sealed compressible air chamber within said generator, compressible to smaller volume by increasing gas pressure within the generator, a water compartment above said air chamber, the water level in which is affected by variations in size of said air chamber, flexible resilient means permanently separating said air chamber and water compartment and means outside of said generator for adjusting the predetermined gas pressure adapted to be automatically maintained within said generator.

12. An acetylene gas generator comprising a generating tank including upper and lower portions, means for clamping and sealing said portions together, a gas compartment in said upper portion, a safety valve release connected with said gas compartment, a supply passageway leading from said gas compartment, a valve for closing said supply passageway, an expandible and contractable sealed air compartment in said lower portion of said generator below the water level variable in size proportional to decreases and increases, respectively, in gas pressure in said gas compartment, a calcium carbide support suspended above said air cell, a water compartment above said air compartment, said sealed air compartment providing means for regulating the water level in said water compartment automatically within said generator by variations in volume of said air compartment in accordance with variations in the pressure of acetylene gas therein to start and stop the generation of gas to maintain a predetermined gas pressure within said generator, and flexible resilient partition means permanently separating said air compartment and water compartment.

13. An acetylene gas generator including a sealed tank portion, a support within said tank for calcium carbide adapted to form gas when contacting water, and a hermetically sealed compressible air compartment below the water level variable in size in inverse proportion to the variations in size of said air cell and adapted to form an air cushion within said generator, flexible resilient partition means permanently separating said air compartment from the remainder of said tank, said generator operating to maintain automatically a predetermined gas pressure within the same by varying the water level while sufficient calcium carbide remains within said generator.

ROLLAND C. SABINS.
